ODDS RATIO RELAY UNIT FOR RACE
TOTALIZATORS

Awdry Francis Julius, Sydney, New South Wales, Australia, and George Alfred Julius, deceased, late of Sydney, New South Wales, Australia, by Eva Dronghsia Odierna Julius, Killara, near Sydney, New South Wales, and Awdry Francis Julius and Russell Stuart Hicks, Sydney, New South Wales, Australia, executors, assignors to Automatic Totalisators Limited, Sydney, New South Wales, Australia

Application June 30, 1948, Serial No. 36,169
In Australia June 30, 1947

2 Claims. (Cl. 318—32)

1

This invention relates to "odds" relay units for race totalisators. Such units are used forelaying, with necessary power magnification, the odds ratio (prevailing at any instant of a totalisator transaction run in respect of a particular competitor in the event for which totalisator transactions are being effected) from an odds ratio computing unit to one or more odds indicators or "barometers" which may be viewed by investors and prospective investors. The odds computing unit manifests its operation in terms of the paying out or hauling in of a tensed cable, cord or other flexible (but substantially inextensible) tension member, the effective length of this member being directly proportional to the odds ratio obtaining for the particular competitor at any given moment of operation.

Odds relay units as used heretofore are efficient at the expense of considerable adjustment and sustained maintenance and servicing if they are to be kept functioning in an accurate and reliable manner. Moreover, the prior relay units are expensive to manufacture, largely due to the mechanical complexity of the reversing switch arrangements and the operating elements associated therewith.

The object of this invention is to overcome the cited shortcomings in the provision of an odds ratio relay unit which by comparison with those used heretofore is of more simple and inexpensive construction and is more reliable and sensitive in operation.

An odds ratio relay unit according hereto may be summarised as comprising, a pair of spring-loaded switches each having alternative circuit closure positions, a reversible electric motor circuited with these two switches in such manner that the direction of motor rotation is contingent upon which of the switch closure positions is obtaining, a pair of cam followers respectively associated with the switches, a cam which through the agency of the two followers is able to effect concerted opening and closing of the switches, means for turning the cam in consonance with an odds ratio variation manifested by an odds computer, and means operable by the motor for actuating an odds indicator and for reverting the cam to a neutral position in which both of the switches are held open.

An example of the invention is illustrated by the drawings herewith.

2

Figure 1 is a side elevation of an odds ratio relay unit.

Figure 2 is a plan projected from Figure 1.

Figure 3 is an end elevation projected from Figure 1, looking from the left of that figure.

Figure 4 is a schematic perspective view showing the main parts of the unit shown by Figures 1 to 3.

Figure 5 is a circuit diagram of the motor and switch arrangements.

The relay unit subject hereof comprises a gear and switch assemblage of which the several parts are mounted in a frame 6 preferably removably secured upon a base 7 by bolting or the like. This base preferably also constitutes a bed for bolting thereto of the reversible electric motor 8 forming part of the relay unit; and, if required, a Selsyn generator 9. The motor and the generator (if present) may be separably coupled to the gear and switch assemblage so that in the event of it being necessary (due to breakdown or otherwise) to remove either the assemblage, the motor or the generator, the affected item may be readily replaced by a reserve item so to avoid undue halting of the installation as a whole.

The frame 6 has a number of shafts in bearings therein. The first shaft 10 has a driving sheave 11 and a resetting gear 12 freely revolubly mounted thereon. The sheave and the gear are respectively fixed to the two face-to-face crown wheels 13 and 14 of an epicyclic gear unit having two planetary pinions 15 which are freely mounted on the arms of a centre cross 16 fixed to the first shaft 10. The driving sheave is weight-loaded by cable 17 and weight 18 and is operated in known manner by a tensed cable 19 from an odds computer which may be of conventional design. The first shaft 10 has a cam disc 20 keyed thereon. This cam disc has about half of its periphery of slightly greater radius (shown exaggerated in Figure 4) than the remainder, so that two smoothly graded peripheral areas of radius change (indicated by 21) are present at substantially diametrically opposite parts thereof. The difference between the two radii of the cam disc may be as little as only a few thousandths of an inch, as described later herein.

Two follower levers 22 and 23 are associated with the cam disc. These follower levers are pivotally mounted (at 24) on the mentioned frame and they have projecting contact spurs

25 able to ride against the cam disc. The two follower levers constitute the operating members for a pair of spring-loaded switches 26 and 27, which are preferably of the spring actuated kind known as micro-switches. The actuating springs of the switches are so arranged that the operating buttons 28 of the switches are at all times loaded to bear against the followers 22 and 23 and hold them in contact with the cam disc 20. The two switches are mounted on the frame 6 and are preferably provided with adjustment screws 29 so that they may be finely adjusted relative to the followers 22 and 23.

The two switches are circuited with the motor 8 as shown in Figures 4 and 5, for operation thereof as described below. The motor is separately drive coupled to a second shaft 30 through a pair of drive plates 31 and 32, one of which is radially slotted to receive a projecting drive peg 33 on the other. Shaft 30 carries a worm pinion 34 meshing a worm wheel 35 on a third shaft 36. A gear train consisting of worm pinion 37, worm wheel 38, pinion 39, gear 40, and pinion 41, drive connects shaft 30 with the re-setting gear 12 fixed to the second crown wheel 14 of the epicyclic gear unit. This gear train includes a fourth shaft 42 carrying a driven sheave 43 to which a cable 44 is connected for the operation of an odds barometer pointer or like movable indicator member. The third shaft 36 may carry a bevel pinion 45 to constitute a separable drive coupling when meshed with a similar or complementary gear 46 on the shaft 47 of the Selsyn generator 9 (assuming such a generator is required and included in the installation).

As previously indicated herein, the two switches are of well-known type, each having (see Figure 5) two stationary contacts 48, 49 and 50, 51 respectively; and a movable contact arm, 52 and 53 respectively. Arms 52 and 53 are connected across the field 54 of the motor 8. The spring loading of arms 52 and 53 is such that they always seek to close on contacts 49 and 50 respectively. Such useless closure is prevented by the cam 20, which compels concerted opening and closing 45 of the switches as described below.

Prior to operation of the unit for relaying of odds ratios, the several parts are in a neutral or non-operating condition. In this condition both of the switches are held open, as shown in Figure 5, by reason of the followers 22 and 23 bearing upon the "mean radius portions" 21 of the cam disc 20. Therefore, the motor is halted, for the time being.

As soon as an odds ratio variation is to be relayed, cable 19 is paid out or hauled in by an odds computer in direct proportion to variations in the odds ratio obtaining in respect of a particular competitor. This initiates a proportional turning of sheave 11 (either due to a pull of cable 19 or a paying out of that cable to enable the weight loading of cable 17 to turn the sheave). As the motor 8 is still halted when sheave 11 commences to turn, the crown wheel 14 is also stationary by reason of it being held by the gear train which includes worm wheel 38 and pinion 37. Thus, the crown wheel 13 by meshing planetary pinions 15 turns the centre cross 16 which in turn part rotates the cam 20.

The direction in which the cam turns will, of course, depend on whether the odds ratio variation represents an "improvement" or a "deterioration" in the odds. In either case the operation of the cam and switch mechanism is identical though opposite in sign. Assuming the cam

5 is turned clockwise as indicated by the arrows in Figure 4, then the follower 22 will ride on to the large radius part of the cam, and the follower 23 will ride on to the small radius part. Thus, the arm 52 will be pressed on to contact 48 by the cam, and arm 53 will be pressed on to contact 50 by its own loading spring.

The resulting operation of the motor turns sheave 43 so that cable 44 actuates the odds barometer or other indicator, and also turns the crown wheel 14. The arrangement is such that when the movement of sheave 11 represents an improvement or a "deterioration" in the odds ratio, then the indicator is operated by cable 44 to display a corresponding improvement or deterioration as the case may be, and the crown wheel 14 in either case is turned in a direction opposite to the immediately prior turning of crown wheel 13 thus reverting (or tending to revert) the centre cross 16 to its initial position in which the cam 20 is neutral and the motor re-halted due to both of the switches again being open. Where several odds barometers or other indicators are to be operated in concert, a Selsyn generator such as 9 is included to actuate the extra indicators in synchronism with the "parent" indicator as well understood.

What we claim is:

1. In a race track totalizer including an odds computer and an odds indicator, a shaft driven from the odds computer, a cam on said shaft, said cam having diametrically opposed rest portions with a raised portion of increased radius therebetween, a pair of single-pole double throw switches each biased to close on one fixed contact, 30 a pair of cam followers operatively connected respectively to the movable contacts of said switches and normally in engagement respectively with the rest portions of said cam to hold the switches in open circuit position and each operable to close the corresponding switch on one fixed contact or to allow said switch to close on the other fixed contact according to the direction of rotation of said cam, a motor for driving the odds indicator, and a field circuit for said motor including one side of a power line and one fixed contact of each of said switches, the movable contacts of both switches and the field, and the other fixed contact of each of said switches and the opposite side of the power line.

2. In a race track totalizer including an odds computer and an odds indicator, aligned first and second shaft sections, a pair of crown gears fixed to the shaft sections and positioned in opposed relationship, a center cross fixed to a first shaft section and rotatably carrying crown pinions meshing with both of said crown gears, a motor having a shunt field, a gear transmission between said motor and the first shaft section, a drive from the transmission to the odds indicator, a sheave on the second shaft section, a weight tangentially connected to said sheave and biasing same in one direction of rotation, a flexible transmission from the odds computer and biasing the sheave in the opposite direction of rotation, a cam on said second shaft section, said cam having diametrically opposed rest portions with a raised portion of increased radius therebetween, a pair of single-pole, double-throw switches each biased to close on one fixed contact, a pair of cam followers operatively connected respectively to the movable contacts of said switches and normally in engagement respectively with the rest portions of said cam to hold the switches in open circuit positions and each operable to close the corre-

sponding switch on one fixed contact so as to allow said switch to close on the other fixed contact according to the direction of rotation of said cam, and a reversing circuit for the motor including the shunt field and both of said single-pole, double-throw switches.
